REFRIGERATING APPARATUS

Edward C. Simmons, Dayton, Ohio, assignor to General Motors Corporation, Detroit, Mich., a corporation of Delaware

Application July 9, 1957, Serial No. 670,678

11 Claims. (Cl. 62—511)

This invention relates to refrigerating apparatus and more particularly to the connections of the suction and supply tubing to refrigerant evaporators.

When copper suction and supply lines are used, it is customary to solder them together to effect a heat exchange. When aluminum tubing is substituted for the suction line to minimize the more difficult soldering, the capillary supply line is extended through the interior of the suction line to effect the heat transfer, as in Patent 2,760,346, issued August 28, 1956. A soldered connection seals the suction line to the evaporator. In some free-flowing evaporators a mere friction fit of the capillary tube in the evaporator is sufficient since it is wholly within the suction line and the evaporator and there is no likelihood of any escape into the room. However, when there is some restriction to flow through the evaporator, the friction fit of the capillary tube in the evaporator is insufficient to preserve the efficiency of refrigeration and to prevent the refrigerant from by-passing of the major portion of the passages of the evaporator.

It is an object of this invention to provide a simple, inexpensive seal of capillary tubing within the evaporator which is easy to install and which readily receives and effectively seals the capillary tube in the evaporator to prevent by-passing.

It is another object of this invention to provide a simple, improved process for sealing the connection of the capillary tube with the refrigerant evaporator.

It is another object of this invention to provide a more economical and efficient series type refrigerating system for two compartments in which the first evaporator is of a plate type and contains two sets of passages, and the second evaporator is located in another compartment and has its passage connected between the two sets of passages in the first evaporator.

These and other objects are attained in the form shown in the drawings in which a T-shaped entrance passageway is arranged with a narrow tapered portion beyond the intersection from the mouth of the passageway. A bushing with an enlarged head preceded by a small shank in turn surrounded and preceded by a longer synthetic rubber sleeve is inserted into the tapered passageway until the head is lodged tightly in the taper. The capillary tube is inserted through the flare-mouth passageway in the head of the bushing until the end expands the sleeve and protrudes beyond the sleeve. The end of the rubber sleeve grips the capillary tube to seal the tube through the sleeve and the bushing to the evaporator.

Further objects and advantages of the present invention will be apparent from the following description, reference being had to the accompanying drawings, wherein a preferred form of the present invention is clearly shown.

In the drawings:

Figure 1 is a development view of an evaporator together with the refrigerant tube connections embodying my invention, and a compressor-condenser unit;

Figure 2 is a front view of the formed evaporating sys-

tem located in a two-compartment refrigerator diagrammatically illustrated;

Figure 3 is an enlarged fragmentary sectional view of a connection embodying my invention taken along the lines 3—3 of Figure 1;

Figure 4 is an enlarged fragmentary sectional view of another connection embodying my invention, taken along the lines 4—4 of Figure 1;

Figure 5 is an enlarged sectional view of the portion 10 of the evaporator corresponding to the lines 4—4 of Figure 1 prior to the formation of the taper in the entrance thereof;

Figure 6 is a fragmentary sectional view taken along the line 6—6 of Figure 5;

Figure 7 is an enlarged fragmentary sectional view also corresponding to the lines 4—4, of the same portion of the evaporator showing the operation of forming the taper in the neck portion of the passage;

Figure 8 is a sectional view along the line 8—8 of 20 Figure 7;

Figure 9 is an enlarged sectional view similar to Figures 4, 5 and 7, also corresponding to the lines 4—4 of Figure 1, showing the bushing fitted in the tapered passage and the capillary tubing in the process of being inserted 25 into the bushing; and

Figure 10 is a sectional view of the bushing alone.

Referring now more particularly to Fig. 1, there is shown a refrigerating system including a sealed motor-compressor unit 20 having an outlet connecting with the condenser 22. The outlet of the condenser 22 is connected to a capillary tube 24. The suction inlet of the compressor 20 is provided with a short piece of suction tubing 26. The capillary tube 24 extends into and through the suction conduit 28. The suction tube 26 connects and 35 forms a sealed connection with the adjacent end of the suction conduit 28 at the same point as the entrance of the capillary tube 24. The opposite end of the suction conduit or tube 28 fits into and is joined and soldered to the common entrance and exit 30 of the roll bonded plate-type evaporator 32 shown developed in Fig. 1 and formed into a rectangular box in Fig. 2. The common entrance and exit 30 extends into a T-shaped passage arrangement 34 having a restricted portion 36 of reduced diameter beyond the intersection of the passageway 38 which connects to the combined entrance and exit 30.

The evaporator 32 is made by the roll bonding process disclosed in Patent 2,712,736 issued July 12, 1955. The evaporator includes hydraulically expanded passageways including the aforementioned passageways 30, 34, 36 and 38. To prevent by-passing of the refrigerant between the capillary tube 24 and the adjacent end of the suction tubing 28, I force a sealed bushing 42 within the portion 36. To accomplish this, before the connections are made, a slightly tapered tool 40 is forced through the entrance 30 into the restricted passageway 36 to shape it into a slightly tapered passageway of circular cross-section, shown exaggerated in Figs. 7 and 8. Preferably, the tool 40 has a 0° 19" taper providing an included angle of 0° 38". The large end, of course, is toward the entrance 30. After the tool 40 is withdrawn, a bushing 42 of the type shown in Fig. 10 is inserted through the entrance 30 into the tapered portion 36 until the rubber sleeve 48 of the bushing fits tightly within the tapered portion 36.

Extending inwardly from the head 44 of the bushing 42 is a straight or tapered shank portion 46 forced into and enlarging a resilient elastic sleeve 48 of an elastomer such as a suitable synthetic rubber such as polymerized chloroprene known as "neoprene" or butadiene. The greater portion of the sleeve 48 is enlarged by the insertion of the shank 46 therein. If desired, this sleeve 48 may be bonded to the shank 46. This rubber sleeve 48

has a normal internal diameter which is smaller than the capillary tube 24. This sleeve 48 extends inwardly beyond the shank 46 a considerable distance for gripping the tube 24, as shown in Fig. 10. The shank 46 enlarges the sleeve 48 sufficiently so that it is slightly larger than the head 44 to tightly fit the interior of the passageway 36. The head 44 serves as a stop to limit the squeezing of the sleeve 48. The sleeve 48 is spaced slightly from the head 44 to provide a space into which the sleeve can flow under compression. The head and shank 44 and 46 are preferably made of some suitable metal such as copper or aluminum, but if desired, may be made of some suitable plastic. The head 44 is provided with a flared entrance 50 connecting directly with a concentric passageway 52 extending axially through the head and shank 44, 46 of the bushing 42. The head 44 provides a tight sealing engagement with the adjacent portion of the tapered passageway 36, as shown in Figs. 9 and 4.

After the bushing 42 is inserted to the position shown in Fig. 9, the capillary tube 24, which may be of copper or aluminum, is inserted through the bushing and beyond, as shown in Fig. 4. The flared entrance 50 guides the capillary tube 24 into the passageway 52 within the bushing 42. The inner end portion of the sleeve 48 tightly envelopes and grips the capillary tube 24 while the enlarged outer surface of the sleeve 48 tightly fits the passageway 36 so as to provide a seal between the capillary tube 24 and the passageway 36, regardless of any variations in the size of the capillary tubing 24. The capillary tubing 24 may have a slight clearance between it and the passage 52 sufficient to provide ease of insertion and threading through the bushing. After this the adjacent end of the suction line 28 is sealed to the entrance portion 30 by soldering, to form a hermetic seal.

From the restricted portion 36, the passageway 54 continues and leads to the parallel passageways 56 extending across the top portion of the evaporator when formed as in Fig. 2. These parallel passageways 56 connect to a single passageway 58 extending around the right side and connecting with the multiple passageways 60 provided in the bottom portion. These multiple passageways 60 again connect to a single passageway 62 which extends through the bottom portion of the left side and thence back across the bottom and up the right side to the multiple passageway 64 in the top connecting with a single passageway 66 leading to the second combined exit and entrance 68.

The passageway 66 has forced therein a bushing 70 similar to the bushing 42 shown in Fig. 10. The end portion of the passageway 66 is tapered as shown by the reference character 72 in an operation similar to that illustrated in Figs. 7 and 8, so that the outer surface of the sleeve 78 of the bushing 70 will fit tightly the walls of the passageway 66. The bushing 70 is also provided with a shank portion 76 which may be straight or tapered, and which extends into and enlarges one end of the sleeve 78 of resilient elastic synthetic rubber while the other end extends beyond. Fitted into the bushing 70 is the end of a liquid tube 80 extending through the coaxial passage in the head 74 and the shank 76 and beyond the end of the synthetic rubber sleeve 78, as shown in Fig. 3. The rubber sleeve 78 has a normal inner diameter smaller than the outer diameter of the tube 80 for gripping the tube 80, and an outer diameter surrounding the shank 76 which is slightly larger than the head 74. The sleeve 78 will be squeezed between the shank 76 and the walls of the passageway 66 until the head 74 contacts the passageway 66.

The tube 80 extends out through the entrance-way 68 through the interior of larger tubing 82 to a plate-type evaporator 84 having a combined entrance and exit 86 and a loop-shaped passageway 88. This evaporator 84 may also be made by the roll bonding process disclosed in Patent 2,712,736 issued July 12, 1955. The combined exit and entrance 86 is provided with a tapered passage portion and a tapering operation and a bushing similar to

the tapered passage 72 and the bushing 70 shown in Fig. 3. The outer tube 82 is joined by solder at the entrance 86 to the evaporator 84 and at the entrance 68 to the evaporator 32. The liquid refrigerant passing through the passage 66 passes through the liquid tube 80 to the plate evaporator 84 and through the passage 88 therein. The liquid tube 80 carries the cold evaporated refrigerant from the plate evaporator 32 as well as any unevaporated liquid refrigerant. Substantially all of the remaining liquid refrigerant will be evaporated in the passage 88 of the plate evaporator 84 and all the refrigerant will return through the entrance 86 and the tube 82 to the entrance 68 in the evaporator 32. The refrigerant within the tube 82 shields the liquid tube 80 and its contents from the air. This refrigerant then connects to a branch passage 90 extending laterally from the entrance 68 across the top of the evaporator to the accumulator 92 located on the right side thereof. This accumulator consists of a plurality of closely spaced passageways. It serves to collect any liquid refrigerant which may not have been previously evaporated. It also serves to condense evaporated refrigerant from the plate evaporator 84 during short defrosting periods, thereby assisting in the defrosting of the plate evaporator 84. The opposite side of the accumulator is connected by the passage 38 to the entrance 30.

The evaporator 32 is located in the upper compartment of a refrigerator 94, diagrammatically shown in Fig. 2, and serves as a freezing compartment. The tubing 80 and 82 extends downwardly to the plate evaporator 84 located in the above-freezing food compartment 96 below the freezing compartment enclosed by the evaporator 32. This refrigerating system is thermally efficient and easy to manufacture and assemble by reason of the connection of the plate evaporator 84 between the passages 66 and 98 of the evaporator 32 and by the concentric liquid and gas-carrying concentric tubing and the three sealing bushings provided in the common entrance and exit passageways.

While the form of embodiment of the invention as herein disclosed constitutes a preferred form, it is to be understood that other forms might be adopted, as may come within the scope of the claims which follow.

What is claimed is as follows:

1. In a refrigerating system, an evaporator having a refrigerant passage therein provided with a common entrance and exit, a suction line connecting with said common entrance and exit, the initial portion of said passage within said entrance having a bushing therein with an enlarged portion in said passage, said bushing having a passage therethrough and a reduced portion extending from said enlarged portion, a liquid tube extending within said suction line through said entrance and said passage in said bushing and protruding from said bushing a substantial distance, and a resilient flexible sleeve enveloping snugly the reduced portion of said bushing and the adjacent portion of said liquid tube and fitting snugly within said passage for sealing the liquid tube to the passage in said evaporator, and refrigerant liquefying means for supplying liquid refrigerant to said liquid tube and for withdrawing evaporated refrigerant from said suction line.

2. In a refrigerating system, an evaporator having a refrigerant passage therein provided with a common entrance and exit, a suction line connecting with said common entrance and exit, the initial portion of said passage within said entrance having bushing means therein provided with an enlarged portion fitting snugly within said passage and a reduced portion extending from the enlarged portion, said bushing means having a passage extending therethrough and an annular resilient part in said reduced portion, a liquid tube extending within said suction line through said entrance and said passage in said bushing means and fitting snugly within said resilient part, and refrigerant liquefying means for supply-

ing liquid refrigerant to said liquid tube and for withdrawing evaporated refrigerant from the suction line.

3. In a refrigerating system, an evaporator having a refrigerant passage therein provided with a common entrance and exit, a suction line connecting with said common entrance and exit, the initial portion of said passage within said entrance having bushing means therein provided with an enlarged portion fitting snugly within said passage and a reduced portion extending from the enlarged portion, said bushing means having a passage extending therethrough and an annular resilient part in said reduced portion, a liquid tube extending within said suction line through said entrance and said passage in said bushing means and fitting snugly within said resilient part, and refrigerant liquefying means for supplying liquid refrigerant to said liquid tube and for withdrawing evaporated refrigerant from the suction line, said bushing means having its resilient part composed of an elastomer.

4. In a refrigerating system, an evaporator having a refrigerant passage therein provided with a common entrance and exit, a suction line connecting with said common entrance and exit, the initial portion of said passage within said entrance having bushing means therein provided with an enlarged portion fitting snugly within said passage and a reduced portion extending from the enlarged portion, said bushing means having a passage extending therethrough and an annular resilient part in said reduced portion, a liquid tube extending within said suction line through said entrance and said passage in said bushing means and fitting snugly within said resilient part, and refrigerant liquefying means for supplying liquid refrigerant to said liquid tube and for withdrawing evaporated refrigerant from the suction line, said bushing means having its enlarged portion relatively hard and its resilient part relatively soft and flexible and elastic.

5. In a refrigerating system, an evaporator having a refrigerant passage therein provided with a common entrance and exit, a suction line connecting with said common entrance and exit, the initial portion of said passage within said entrance having bushing means therein provided with an enlarged portion fitting snugly within said passage and a reduced portion extending from the enlarged portion, said bushing means having a passage extending therethrough and an annular resilient part in said reduced portion, a liquid tube extending within said suction line through said entrance and said passage in said bushing means and fitting snugly within said resilient part, and refrigerant liquefying means for supplying liquid refrigerant to said liquid tube and for withdrawing evaporated refrigerant from the suction line, said bushing means having its passage provided with a flared mouth.

6. In a refrigerating system, an evaporator having a refrigerant passage therein provided with a common entrance and exit, a suction line connecting with said common entrance and exit, the initial portion of said passage within said entrance having bushing means therein provided with an enlarged portion fitting snugly within said passage and a reduced portion extending from the enlarged portion, said bushing means having a passage extending therethrough and an annular resilient part in said reduced portion, a liquid tube extending within said suction line through said entrance and said passage in said bushing means and fitting snugly within said resilient part, and refrigerant liquefying means for supplying liquid refrigerant to said liquid tube and for withdrawing evaporated refrigerant from the suction line, said bushing means having its passage provided with a portion having a metal surface.

7. In a refrigerating system, an evaporator having a refrigerant passage therein provided with a common entrance and exit, a suction line connecting with said common entrance and exit, the initial portion of said

passage within said entrance having bushing means therein provided with an enlarged portion fitting snugly within said passage and a reduced portion extending from the enlarged portion, said bushing means having a passage extending therethrough and an annular resilient part in said reduced portion, a liquid tube extending within said suction line through said entrance and said passage in said bushing means and fitting snugly within said resilient part, and refrigerant liquefying means for supplying liquid refrigerant to said liquid tube and for withdrawing evaporated refrigerant from the suction line, said initial portion of said refrigerant passage being tapered.

8. In a refrigerating system, an evaporator having a refrigerant passage therein provided with a first common entrance and exit, a suction line connecting with said first common entrance and exit, the initial portion of said passage within said entrance having bushing means therein provided with an enlarged portion fitting snugly within 15 said passage and a reduced portion extending from the enlarged portion, said bushing means having a passage extending therethrough and an annular resilient part in said reduced portion, a liquid tube extending within said suction line through said entrance and said passage in said 20 bushing means and fitting snugly within said resilient part, and refrigerant liquefying means for supplying liquid refrigerant to said liquid tube and for withdrawing evaporated refrigerant from the suction line, a second evaporator having a refrigerant passage therein having a common 25 entrance and exit, said first mentioned evaporator being provided with an accumulator passage therein embodied in said refrigerant passage and connecting with said first exit and a second common entrance and exit with said refrigerant passage including a passage extending 30 from said second entrance to said accumulator passage and a passage connection between the initial portion of said refrigerant passage and said second exit, large tubing connecting the exit of said second evaporator to the second common entrance of the first mentioned evaporator, smaller tubing extending within said large tubing connecting the second exit of said first mentioned evaporator and said entrance of said second evaporator.

9. In a refrigerating system, an evaporator having a refrigerant passage therein provided with a first common entrance and exit, a suction line connecting with said first common entrance and exit, the initial portion of said passage within said entrance having bushing means therein provided with an enlarged portion fitting snugly within said passage and a reduced portion extending from the enlarged portion, said bushing means having a passage extending therethrough and an annular resilient part in said reduced portion, a liquid tube extending within said suction line through said entrance and said passage in said bushing means and fitting snugly within said resilient part, and refrigerant liquefying means for supplying liquid refrigerant to said liquid tube and for withdrawing evaporated refrigerant from the suction line, a second evaporator having a refrigerant passage therein having a common entrance and exit, said first mentioned evaporator being provided with an accumulator passage therein embodied in said refrigerant passage and connecting with said first exit and a second common entrance and exit with said refrigerant passage including a passage extending from said second entrance to said accumulator passage and a passage connection between the initial portion of said refrigerant passage and said second exit, large tubing connecting the exit of said second evaporator to the second common entrance of the first mentioned evaporator, smaller tubing extending within said large tubing connecting the second exit of said first mentioned evaporator and said entrance of said second evaporator, and a bushing in said second common entrance and exit surrounding said smaller tubing and having a tubular extension of an elastomer snugly fitting and providing a seal with said smaller tubing.

10. In a refrigerating system, an evaporator having a refrigerant passage therein provided with a first entrance and a first exit, a suction line connecting with said exit, a liquid tube connecting with said entrance, refrigerant liquefying means for supplying liquid refrigerant to said liquid tube and for withdrawing evaporated refrigerant from the suction line, a second evaporator having a refrigerant passage therein having a common entrance and exit, said first mentioned evaporator being provided with a common second entrance and exit and said refrigerant passage including a passage extending from said common entrance and exit to said first entrance and a passage extending from said common entrance and exit to said first exit, large tubing connecting the exit of said second evaporator to the common entrance of said first mentioned evaporator, smaller tubing extending within said large tubing connecting the common exit of said first mentioned evaporator and said common entrance of said second evaporator, and a bushing in said common entrance and exit of said second evaporator surrounding said smaller tubing and having a tubular extension composed of an elastomer snugly fitting and providing a seal with said smaller tubing.

11. In a refrigerating system, an evaporator having a refrigerant passage therein provided with a first entrance 25 and a first exit, a suction line connecting with said exit, a liquid tube connecting with said entrance, refrigerant liquefying means for supplying liquid refrigerant to said liquid tube and for withdrawing evaporated refrigerant

5
